UNITED STATES PATENT OFFICE

2,473,169

REFRIGERATOR CAR WITH A MOBILE BULKHEAD

Charles L. Moorman, Millington, Ill., assignor to
Union Asbestos & Rubber Company, a corpora-
tion of Illinois

Application October 22, 1945, Serial No. 623,714

5 Claims. (Cl. 62—19)

1

This invention relates to refrigerator cars and the like and more particularly to cars of this type provided with convertible or movable bulkheads.

One of the objects of the invention is to provide a refrigerator car in which a single rack serves both as a floor rack for the car and as a liner for the bulkhead.

Another object is to provide a refrigerator car in which the rack provides a support for an ice grate when it is in a position for use as a bulkhead liner.

Still another object is to provide a mounting construction for the rack by which it is enabled to carry substantial loads without requiring an elaborate or expensive pivotal mounting construction.

The above and other objects and advantages of the invention will be more readily apparent from the following description when read in connection with the accompanying drawing, in which—

Figure 1 is a partial longitudinal section through a refrigerator car equipped with the present invention showing the bulkhead in extended position; and

Figure 2 is a view similar to Figure 1 with the bulkhead in retracted position.

The invention is adapted to be utilized in connection with a conventional refrigerator car having an end wall construction 10 and provided with lading racks 11 extending longitudinally of the car and terminating short of the ends thereof. The car carries a movable bulkhead indicated generally at 12 which may be supported on tracks or the like adjacent the top of the car to be moved from an extended to a retracted position. The mounting of the bulkhead is preferably such that it can be raised for movement and can be lowered when in either its extended or retracted position. To hold the bulkhead against movement when it is lowered, a transverse channel shaped foot member 13 is secured to the lower edge of the bulkhead to fit between transversely extending beams 14. When it is in its lowered position, the bulkhead may be held against accidental raising by a latch plate 15 controlled by an operating rod 16, as more particularly described and claimed in my co-pending application, Serial No. 623,715, filed October 22, 1945.

The transverse beam members 14 are carried by longitudinally extending supporting beams 17 which may be of inverted channel shape and cut out along their lower edges to provide for free circulation of air. The beams 17 extend

2

substantially from the end of the floor rack 11 to the end of the car.

To provide a floor in the space between the end of the floor rack and the end of the car when the bulkhead 12 is in its retracted position, as shown in Figure 2, a pivotally mounted floor rack is provided. As shown, the floor rack comprises a perforated screen member 18 which may be formed of perforated or expanded sheet-metal and which is of a size to fill the space above the beams 17 between the end of the lading rack 11 and the beam 14 adjacent the end of the car. The screen 18 is adapted to rest at one end on filler strips 19 secured to the beams 17 and extending a distance equal to substantially half the length of the screen. The opposite end of the screen is supported by reinforcing beams 21 extending from the pivoted end of the screen throughout substantially the other one-half of its length. The reinforcing beams 21 engage a transversely extending angle beam 22 secured to the lower surface of the screen for a purpose to appear later.

According to the present invention, the screen 18 is adapted, when in its horizontal position as shown in Figure 2, to provide a continuation of the lading rack 11 so that the car can be loaded substantially from end to end. When the car is used as a refrigerator car, the bulkhead is extended to the position shown in Figure 1. At this time the screen 18 is swung about its pivotal mounting to a vertical position in which it provides a liner for the inner surface of the bulkhead. When in the vertical position, the screen also serves as a support for an ice grate 23 which is pivoted at 24 to the end of the car and which rests at its opposite end on the support 22. It will be seen that in this position the reinforcing beams 21 carry the support 22 so that no excessive loads are placed on the screen which might cause it to bend or buckle. If desired, a second ice grate 25 may be provided above the ice grate 23 supported on a bracket 26 on the bulkhead for stage icing.

The floor rack is pivotally supported adjacent the end of the lading rack 11 by providing on the floor rack one or more arcuate arms 27 connected to the floor rack at points spaced from its end and extending through openings 28 in the beams 17. The arms 27 serve to guide and support the floor rack during its pivotal movement and are so constructed that when the floor rack is in its vertical position, as shown in Figure 1, the lower edge of the screen 18 and the lower ends of the reinforcing beams 21 rest directly on

the beams 17. With this construction the weight of the ice grate 23 and the ice carried thereby is directly supported on the beams 17 through the beams 21 and the support 22 so that a light screen can be used at 18 without liability of damage.

While one embodiment of the invention has been shown and described in detail, it will be understood that this is illustrative only and is not intended as a definition of the scope of the invention, reference being had for this purpose to the appended claims.

What is claimed is:

1. In a refrigerator car or the like having a lading rack above its floor and terminating at a point spaced from the end of the car, a bulkhead in the car extending substantially from the top to the bottom thereof and mounted for movement from a retracted position adjacent the end of the car to an extended position adjacent the end of the lading rack, a transversely extending beam adjacent the end of the lading rack and in horizontal alignment therewith to support the bulkhead when it is in its extended position, and a floor rack pivoted adjacent the end of the lading rack for movement from a horizontal position in which it forms a continuation of the lading rack to a vertical position against the inner surface of the bulkhead when the bulkhead is in its extended position.

2. In a refrigerator car or the like having a lading rack above its floor and terminating at a point spaced from the end of the car, a bulkhead in the car mounted for movement from a retracted position adjacent the end of the car to an extended position adjacent the end of the lading rack, a supporting beam extending substantially from the end of the lading rack to the end of the car, a floor rack supported on the beam, and an arcuate arm on the floor rack extending through an opening in the beam to guide the floor rack for pivotal movement from a horizontal position aligned with the lading rack to a vertical position against the inner surface of the bulkhead when the bulkhead is in its extended position.

3. In a refrigerator car or the like having a lading rack above its floor and terminating at a point spaced from the end of the car, a bulkhead in the car mounted for movement from a retracted position adjacent the end of the car to an extended position adjacent the end of the lading rack, a supporting beam extending substantially from the end of the lading rack to the end of the car, a floor rack supported on the beam, and an arcuate arm on the floor rack extending through an opening in the beam to guide the floor rack for pivotal movement from a horizontal position aligned with the lading rack to a vertical position against the inner surface

of the bulkhead when the bulkhead is in its extended position, and the end of the floor rack resting on the beam when it is in its vertical position, and a support on the floor rack to support one end of an ice grate.

4. In a refrigerator car or the like having a lading rack above its floor and terminating at a point spaced from the end of the car, a bulkhead in the car mounted for movement from a retracted position adjacent the end of the car to an extended position adjacent the end of the lading rack, a relatively thin perforated screen pivotally mounted adjacent the end of the lading rack and movable from a horizontal position to a vertical position against the inner surface of the bulkhead when the bulkhead is in extended position, a beam extending across the lower surface of the screen to support one end of an ice grate when the screen is in vertical position, reinforcing beams extending from the pivotally mounted end of the screen to the last named beam and supporting beams extending substantially from the end of the lading rack to the end of the car on which the screen is supported when it is in its horizontal position, the lower ends of the reinforcing beams resting on the supporting beams when the screen is in its vertical position.

5. In a refrigerator car or the like having a lading rack above its floor and terminating at a point spaced from the end of the car, a bulkhead in the car mounted for movement from a retracted position adjacent the end of the car to an extended position adjacent the end of the lading rack, supporting beams extending substantially from the end of the lading rack to the end of the car, a relatively thin perforated screen supported by the beams to form a continuation of the lading rack, an arcuate arm on the screen extending through an opening in one of the beams to guide the screen for pivotal movement from the horizontal position to a vertical position against the inner surface of the bulkhead when the bulkhead is in its extended position, a transverse support on the lower surface of the screen to support one end of an ice grate, and reinforcing beams extending from the pivotally mounted end of the screen to the support, the end of the screen and the reinforcing beams resting directly on the supporting beams when the screen is in vertical position.
